UNITED STATES PATENT OFFICE.

DAVID M. PARRY, OF INDIANAPOLIS, INDIANA.

HUB-BORING MACHINE.

SPECIFICATION forming part of Letters Patent No. 397,816, dated February 12, 1889.

Application filed April 21, 1888. Serial No. 271,408. (No model.)

To all whom it may concern:

Be it known that I, DAVID M. PARRY, a citizen of the United States, residing at Indianapolis, in the county of Marion and State 5 of Indiana, have invented certain new and useful Improvements in Hub-Boring Machines, of which the following is a specification.

The object of my said invention is to produce a machine by means of which the holes 10 in the hubs of wheels into which the boxing or skeins are to be inserted can be quickly and accurately bored; and it consists in a simple and effective clamping and centering device, whereby the wheel is brought accurately 15 to the position to be bored, and there held securely during the operation of boring the hub.

It further consists in certain details of construction, all as will be hereinafter more particularly described and claimed.

Referring to the accompanying drawings, 20 which are made a part hereof, and on which similar letters of reference indicate similar parts, Figure 1 is a side elevation of a machine embodying my said invention; Fig. 2, a central vertical sectional view looking toward the 25 right from the dotted line 2 2 in Fig. 1 and upwardly from the same dotted line in Fig. 3; Fig. 3, a horizontal sectional view looking downwardly from the dotted line 3 3 in Figs. 30 1 and 2; Fig. 4, a detail sectional view similar to a portion of Fig. 2, but on an enlarged scale; and Fig. 5, a detail sectional view looking upwardly from the dotted line 5 5 in Fig. 3.

In said drawings the portions marked A represent the frame-work of the machine; B, the 35 shaft to the upper boring-tool; C, the shaft to the lower boring-tool; D, the bearing in which the center of the clamp for the wheel is mounted, and E said clamp-center.

The frame A consists of an upright portion, 40 upon which are bearings for the shafts B and C, and a horizontal portion forming a table upon which the wheel to be operated upon is placed, which latter portion carries the bearing for the clamp, and also supports the arms of said clamp.

The shaft B carries the upper boring-tool, b, 45 which commonly does the greater part of the work. It is mounted in bearings B' and B² upon the frame A, and between said bearings upon said shaft is placed a pulley, B³, through

which the shaft may freely move longitudinally, but which is kept from revolving on said shaft by means of a spline, and said shaft is driven by means of a suitable belt, b³, running to this pulley. Said shaft and the boring-tool, b, carried thereby are operated vertically by means of a lever, B⁴, which is pivoted to an arm, A⁴, on the frame, and connected to said shaft by a link, b⁴, and an intermediate lever, 55 B⁵, which is connected to a sleeve, b⁵, on said shaft, and pivoted to an arm, A⁵, on the frame-work by a pivot, a⁵. A counter-balance, B⁶, is preferably provided, by which the shaft and the tool thereon are held up out of the way, 60 except when forced down by the operator by means of the lever.

The shaft C carries the lower boring-tool, c, which generally is used only to trim out the end of the hub to receive the nut which (after 70 the wheel is completed and placed on the axle) is placed on the end of the axle to hold the wheel thereon. It is mounted in bearings C' and C² on the frame A, provided with a pulley, C³, and driven by the belt c³ in a similar 75 manner as the shaft B is mounted and driven. It is operated by means of a lever, C⁴, which is pivoted to the frame-work and engages with said shaft, as shown. It is kept down out of engagement by its own weight, except when 80 forced up by the operator, and therefore needs no counter-balance.

The bearing D is in the form of a heavy ring, and is fixedly secured centrally upon the portion of the frame-work forming the table 85 upon which the wheels are placed while being operated upon and supports the clamp-center firmly in position.

The clamp is composed of a central portion, E, and several arms, (preferably four,) 90 E', E², E³, and E⁴, and an arm or lever, E⁵, by which it is operated. The clamp-arms are pivoted at their inner ends tangentially upon the center E, and their outer ends rest in bearings upon the frame-work, as shown. The operating arm or lever E⁵ is secured rigidly to said center and extends out to near where the operator is intended to stand. It preferably has a suitably-formed edge to engage with a rack-bar, a, upon the frame-work, (see Fig. 3,) and 100 thus the clamp is held firmly into engagement with the wheel.

The operation is generally as follows: The machine being in operation and the wheel being ready to have its hub bored out, said wheel is placed upon the machine. The handle or lever E^5 is then swung around until the turned-up ends of the clamp-arms come tightly against the periphery of the wheel, which not only clamp the wheel firmly in position, but bring the center of its hub exactly below the center of the boring-tool b . The shaft B is then forced down by means of the handle or lever B^4 , and the boring-tool thus caused to finish the hole in the hub. After this is done the shaft C , carrying the boring-tool c , is forced up by means of the lever C^4 , and the other end of the hub is thus finished. The handle or lever E^5 is then disengaged from the rack a , said lever swung back, opening the clamp, the wheel removed, and the operation repeated, which, as will be readily understood, is a very simple one, which can be rapidly and economically performed.

Having thus fully described my said invention, what I claim as new, and desire to secure 25 by Letters Patent, is—

1. The combination, in a hub-boring ma-

chine, with the boring-tools and means for operating the same, of a clamp for centering and holding the wheel, consisting of a revoluble center having several arms tangentially secured thereto, the outer ends whereof are adapted to engage with the periphery of the wheel, an operating handle or lever, and means for securing it in operative position, substantially as set forth. 30

2. The combination, in a hub-boring machine, of the frame-work, the shaft for the boring-tool, bearings on said frame-work for said shaft, a pulley loosely mounted on said shaft between said bearings and held thereon by a spline, an operating-lever for moving said shaft, and the wheel-clamp consisting of the revoluble center having several arms adapted to engage with the wheel tangentially secured thereto, all substantially as set forth. 35

In witness whereof I have hereunto set my hand and seal, at Indianapolis, Indiana, this 18th day of April, A. D. 1888.

DAVID M. PARRY. [L. S.]
